UNITED STATES PATENT OFFICE.

HERMINE J. BAER, OF SAN FRANCISCO, CALIFORNIA.

FORM-FITTING WAIST-LINING.

No. 882,989.

Specification of Letters Patent. Patented March 24, 1908.

Application filed July 2, 1907. Serial No. 381,907.

To all whom it may concern:

Be it known that I, HERMINE J. BAER, resident of the city and county of San Francisco and State of California, have invented 5 new and useful Improvements in Form-Fitting Waist-Lining, of which the following is a specification.

This invention has for its object to provide for the use of the dress-maker an improved 10 form-fitting waist-lining, having several novel features that give it advantages over those means or methods heretofore employed in the dress-making art.

Among other advantages it reduces the 15 labor of cutting out and sewing, in the feature of having a less number of seams; it enables a waist to be fitted and a perfect fit secured at one operation of fitting to the person, and in much less time than is found 20 practicable when cutting out, basting and fitting according to the methods heretofore practiced in the art; it gives a person of ordinary experience in cutting and sewing garments the advantage of obtaining a perfect 25 fit under different conditions or styles of form or figure, equally as well as is obtained only after several operations of fitting the waist by the experienced dress-maker, and that without calling for special skill or training.

These and other objects and advantages I attain and secure in and by the construction described and set forth in the following specification:

35 The accompanying drawing illustrates a pattern for a waist-lining of my invention, Figure 1 being a pattern for cutting out one-half of the lining, and including in one piece the front, side and back of one-half of the 40 lining; and Fig. 2 being a pattern for that part of the waist-lining which I have termed the corselet. Fig. 3 is a view, on a smaller scale, of the waist-lining arranged to open at the back, and closed at the front, and after 45 the corselet has been attached ready for the operation of fitting the lining to the wearer.

The complete waist-lining of my invention is formed or composed of the right and left halves $a-a'$, which are cut to shape on the 50 lines of the pattern Fig. 1, and the band or strip b , which I term the corselet. The two parts $a-a'$ are united by sewing the back-edges c together, and the shoulders are joined in the usual way by bringing the two 55 edges $d-d'$ together; finally the corselet is attached to the back at a point midway of

the ends. The usual whale bones or stiffening means are attached in place, and the lining is ready for the operations of fitting and finishing.

In the pattern Fig. 1 it will be seen that the front 2, the side 3 and the back 4 are integral; thereby calling for but three main seams, namely the two shoulder-seams $d-d'$, and the longitudinal seam by which the two halves are united. In addition to these three seams, however, there are provided two secondary seams on the front of each half of the lining. These two seams 5-5 and 6-6 circumscribe two "darts" e, f , which are so placed that the first-mentioned one provides for taking up more or less of the lining fabric circumferentially at the waist-line, on each side, and the remaining one provides for taking up the fabric longitudinally at the front.

In addition to the perpendicular dart e that extends from the lower edge g upwards, the lining is slit at two points over the hips, as illustrated in Fig. 1 of which the slit 7 in the bottom-edge is located about in line with the lower edge of the arm-hole, and the other one 8 a short distance in front of the slit 7. These slits usually extend in the pattern from the bottom edge upward to the 85 normal waist-line indicated by the dotted line 10, but they are continued or extended above that line a greater or less distance as may be found necessary to shorten the waist.

The corselet b which is attached to the 90 lining at the back after the two halves $a-a'$ are united, is first drawn around the waist of the person being fitted and temporarily fastened in place at the ends, after which the lining is taken in at the darts $e-e'$, and otherwise drawn in or let out at the slits 7-8 by folding in the tabs 12, 13, 14, or by prolonging the slits, and the parts are temporarily fastened to the corselet as the fitting proceeds. At the end of that operation the 100 fitted lining is removed, and the corselet is permanently secured to the lining-fabric by lines of stitching at and along the waist-line 10, from back to front. This corselet and the manner of combining and joining it with the waist-lining is an important feature of the invention. As it is placed on the inside of the lining covering the seams at the waist-line, it also takes the place of a facing. Its chief function or purpose, however, is to hold 105 the folds and parts of the lining in the required positions or relations to fit the form

during the operation of fitting the lining, and afterwards to so retain the same in shape by being made a permanent part of the lining.

The same pattern is adapted for a waist 5 to be opened at the back, simply by uniting the two halves $a-a'$ at the longitudinal front seam h , and placing the hooks and eyes or other fastening means on the back edges c .

A low neck or decolette waist is readily 10 produced from the same pattern by cutting the front 2 on the dotted line 15, and the back 4, on the similar line 16, which are provided in the pattern Fig. 1 for that purpose. This pattern can be printed or stamped on 15 the fabric and furnished in quantities of different standard sizes, ready to be cut out and fitted.

In selecting the proper size of pattern, the 20 dress-maker is guided only by the bust measure of the person to be fit; as the peculiar features of the pattern render it practicable to secure a perfect fit to the form in all degrees of stoutness, spareness or other characteristics.

25 I claim:—

1. The herein described form-fitting waist-lining comprising the separate halves, each having the front, side and back integral, the

two halves and parts being united by the longitudinal edges and at the shoulder seams, 30 and the corselet.

2. In a form-fitting waist-lining, the separate halves each comprising a front, a side and a back cut from a single piece of fabric, and having the perpendicular dart in the 35 front, and the transverse dart on the breast-portion, in combination with the corselet.

3. In a form-fitting waist-lining, the separate halves each comprising a front, a side and a back cut from a single piece of fabric, 40 and having the perpendicular dart in the front, the transverse dart on the breast-portion and slits along the bottom edge in combination with the corselet.

4. The herein described form-fitting waist 45 lining comprising separate halves, each having the front, side and back cut from a single piece of fabric, the said halves being united along their longitudinal edges, in combination with the corselet, substantially as set 50 forth.

HERMINE J. BAER.
